UNITED STATES PATENT OFFICE.

RICHARD D. KNIGHT, OF PROVIDENCE, RHODE ISLAND; GRACE P. KNIGHT EXECUTRIX
OF SAID RICHARD D. KNIGHT, DECEASED.

COMBINED ADVERTISING DEVICE AND TEMPORARY SAVINGS BANK.

Application filed April 28, 1920. Serial No. 377,292.

To all whom it may concern:

Be it known that I, RICHARD D. KNIGHT, a citizen of the United States, and resident of the city of Providence, in the county of

- 5 Providence and State of Rhode Island, have invented certain new and useful Improvements in Combined Advertising Devices and Temporary Savings Banks, of which the following is a specification.
- 10 This invention relates to a combined advertising device and temporary savings bank, and has for its object to provide such a device in which the money-receptacle is in the form of an envelop secured to the back 15 of an advertising card or plate, in such a manner as to permit the coin or money to be deposited therein through a slot in the plate, the envelop being so connected to the back of the plate as to cover the coin slot, 20 and also to permit the envelop to be freely sung out at an angle to the plane of the plate, to serve as a supporting standard therefor, the attaching means being such as to permit the envelop to be as readily swung 25 back to lie flat against the plate, to facilitate shipping.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:—

Figure 1 is a perspective view illustrating my combined advertising device and temporary savings bank, the latter also serving as 40 a standard for supporting the advertising plate in an inclined position.

Figure 2 is a central sectional edge elevation of the device, illustrating a number of coins as having been deposited in the bank.

Figure 3 is a back view of the plate, showing the envelop attached thereto.

Figure 4 is a detail of the envelop, showing the two flaps at the end thereof.

Figure 5 is a perspective view illustrating the strip of material which is fastened over one of the envelop flaps to adjustably secure this flap to the back of the plate.

Referring to the drawings, 10 designates the front plate of the device, which may be

made of paper, cardboard or any suitable material and in any desired shape, but which is usually made in some fanciful or attractive form for advertising purposes.

Through the upper portion of this plate is formed a slot 11 which may be of any suitable size or shape but which is preferably formed narrow, to permit the passing of coins therethrough.

To obtain the savings-bank feature of this device I have provided an envelop 13 which may be of paper, cloth or other suitable material, the same being preferably provided with two flaps or lips 13 and 14, the inner side of flap 14 being preferably gummed whereby it may be cemented and so permanently secured to the back of the plate beneath the slot 11.

The upper lip or flap is turned upwardly to lie against the back of the plate above the slot 11 and is adjustably secured by means of a strip 15 of material, which extends across the flap, the ends of which strip are cemented to the back of the plate at 16 on either side of the flap; by which construction this upper flap may be slid up and down through this slot whereby the envelop may be caused to lie flat against the back of the plate to facilitate storing and shipping the device or when desired the envelop may be swung outwardly into the position illustrated in Figures 1 and 2 to also serve as a standard for supporting the plate in an inclined position, which swinging movement causes the flap 13 to slide beneath its securing strip.

It will be noted that if this flap 13 is not permitted to slide and adjust itself the envelop would not swing readily but would become wrinkled in being moved from one position to the other.

Another feature of this construction is that by the use of this securing strip member when the bank becomes filled and it is desired to remove its contents, the sealing strip may be broken and the contents readily removed; the envelop may then be again sealed by cementing a fresh strip across its upper flap, which operation may be repeated as many times as desired without in any way injuring the envelop.

The device is extremely simple and practical in construction and by its use an attractive advertising device is provided which will be permanently retained by the recipient

on account of its utility, and not thrown away or destroyed as is the fate of many advertising devices.

The foregoing description is directed 5 solely towards the construction illustrated, but I desire it to be understood that I reserve the privilege of resorting to all the mechanical changes to which the device is susceptible, the invention being defined and 10 limited only by the terms of the appended claims.

I claim:

1. A combined advertising device and savings bank comprising a front display plate 15 having a coin-receiving slot therethrough, and a coin-retaining envelop having two end flaps extending in opposite directions and secured to the back of said plate on opposite sides of said slot to receive coins passed 20 through the slot into its mouth which is thus held open.

2. A combined advertising device and savings bank comprising a front display plate having a coin-slot therethrough, a coin-re- 25 ceiving envelop having two end flaps, one

permanently and the other adjustably secured to the back of said plate on opposite sides of said slot.

3. A combined advertising device and savings bank comprising a front display plate 30 having a coin-slot therethrough, a coin-receiving envelop having two end flaps, one permanently cemented to the back of said plate on one side of said slot, and a strip secured over the other flap for adjustably 35 securing it to said plate whereby said envelop may be swung out from said plate to serve as a supporting standard therefor and also swing back to lie smoothly against said plate when desired.

4. A combined display device and coin receptacle comprising a display card having a slot therein and an envelope secured to the card and constituting a support for said display card, said envelope having an opening registering with the slot in the display card.

In testimony whereof I affix my signature.

RICHARD D. KNIGHT.
